UNITED STATES PATENT OFFICE

STANLEY WOJTAN, OF CHICAGO, ILLINOIS

TABLE-LEG FASTENING

Application filed February 14, 1929. Serial No. 339,975.

This invention relates to certain new and useful improvements in table leg fastenings and has for its primary object to provide a table construction in which the supporting legs of the table top are easily and quickly removable so that the table structure will occupy a minimum of space during shipment or storage.

A further object of this invention is to provide a table leg fastening in which clamping strips are employed for engaging the table legs when in assembled position on the table top for securely holding them in position, the fastening devices being permanently carried by the table top.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a side elevational view of a table constructed in accordance with the present invention;

Figure 2 is a bottom plan view of the same;

Figure 3 is a longitudinal horizontal sectional view taken on line 3—3 of Figure 1 showing the screw operated clamping strip for the corner legs of the table;

Figure 4 is a vertical longitudinal sectional view through the table top with the legs broken away, showing the overlapped wedged ends of a pair of clamping strips with the operating screw therefor;

Figure 5 is a vertical cross-sectional view taken on line 5—5 of Figure 1, showing the channel guides carried by the table top for the leg clamping strips and the guide screw or pin for the outer end of each strip;

Figure 6 is a fragmentary sectional view, similar to Figure 3, showing the clamping strip in displaced condition with the screws for moving the same away from each other into clamping engagement with the corner legs; and

Figure 7 is a perspective view of one of the clamping strips.

The table comprises a top board 1 having

side and end rails beneath the table top 1 with which the corner legs 2 are detachably connected. The table top and legs are preferably constructed of wood while the side and end rails are of metallic construction, 55 painted or otherwise decorated to correspond with the finish of the wood.

The side and end rails are of channel iron formation and as shown in Figure 3, form a rectangular frame having vertical outer side 60 walls 3 and inwardly directed upper and lower flanges 4 and 5 respectively with the open sides of the channel iron facing each other, the corner portion of the channel iron flanges 5 being cut away as at 6 forming rectangular openings for receiving the rectangular block ends 2^a of the table legs 2. The channel iron side and end rails are suitably secured in any preferred manner to the lower face of the table top 1 by having the upper 65 side flanges 4 anchored to the table top.

A pair of leg retaining strips 7 is confined in each side and end rail 3 as shown in Figure 3, the abutting ends of the strips 7 being reversely beveled as at 8 for wedging contact 70 with each other with each beveled end 8 transversely slotted as at 9 for the passage of an operating screw to be described. The outer end of each leg retaining strip 7 is provided with a vertical slot 10 opening at the 75 end of the strip and through which slot a guide screw 11 passes, the guide screw 11 as shown in Figure 5 passing through openings in the lower and upper flanges 5 and 4 of the side and end rails, and through the slots 10 80 of the leg retaining strips to enter the lower face of the table top 1, the guide screws 11 retaining the outer ends of the leg retaining strips in the channel iron rails. A screw 12 projects laterally from the side wall 3 of the 85 side and end rails and passes through the slotted portions 9 of the overlapping beveled or wedge ends 8 of cooperating leg retaining strips as shown in Figures 3 and 6, the inner projecting end of the screw 12 receiving a washer 13 and thumb nuts 14.

Assuming that the table legs 2 are disengaged from the table top 1, and it being desired to attach them to the table top, the thumb nuts 14 are loosened on the screws 12 100

and the leg retaining strips 7 shifted to the exaggerated position shown in Figure 6. At this time, the block end 2^a of each leg is set into the rectangular opening formed by the cut away portions 6 in the rail flanges 5 and the several thumb nuts are then threaded onto the screws 12 causing the washers 13 to impinge upon the adjacent end of a strip 7 for moving the beveled or wedge ends 8 thereof over each other to cause outward or separating movement of the leg retaining strips 7 with the outer ends thereof bindingly engaging the sides of the end blocks 2^a of the table legs 2, the outer ends of the leg retaining strips 7 being guided in their movement by the guide screws 11. The legs 2 are securely anchored to the side rails of the table top and their rigid support affords a substantial table construction. With a collapsible table of this type, the legs may be easily and quickly removed and suitably confined against the underside of the table top for purposes of storing and shipment to occupy a minimum of space and when the legs are assembled in set up condition on the table, a rigid construction results.

From the above detailed description of the invention, it is believed that the construction and operation thereof will at once be apparent, and while there is herein shown and described the preferred embodiment of the present invention, it is nevertheless to be understood that minor changes may be made therein without departing from the spirit and scope of the invention as claimed.

I claim:—

1. In a table, a table top, side and end rails depending from the top, legs detachably engaged with the table, means carried by the side and end rails for anchoring the legs to the table, said means including a pair of slideable strips on each side and end rail having beveled overlapping ends, and means engaged with the beveled ends for moving the strips away from each other into abutting and binding engagement with the legs.

2. In a table, a table top, side and end rails depending from the top, legs detachably engaged with the table, means carried by the side and end rails for anchoring the legs to the table, said means including a pair of slideable strips on each side and end rail, the adjacent ends of the strips being overlapped and bevelled, and an operating screw and nut associated with the bevelled ends of the strips for moving the bevelled ends over each other to separate the strips and move them into binding engagement with the legs.

3. In a table, a table top, side and end rails depending from the top, legs detachably engaged with the table, means carried by the side and end rails for anchoring the legs to the table, said means including a pair of slideable strips on each side and end rail, the adjacent ends of the strips being overlapped

and bevelled, an operating screw and nut associated with the bevelled ends of the strips for moving the bevelled ends over each other to separate the strips and move them into binding engagement with the legs, and said bevelled ends being slotted for the passage of the screw.

4. In a table, a table top, side and end rails depending from the top, legs detachably engaged with the table, means carried by the side and end rails for anchoring the legs to the table, said means including a pair of slideable strips on each side and end rail, the adjacent ends of the strips being overlapped and bevelled, an operating screw and nut associated with the bevelled ends of the strips for moving the bevelled ends over each other to separate the strips and move them into binding engagement with the legs, the outer ends of the strips having end opening slots, and guide pins for the outer ends of the strip carried by the table top and rail and extending through the end slots.

5. In a table, a table top, side and end rails depending from the top, legs detachably engaged with the table, means carried by the side and end rails for anchoring the legs to the table, said means including a pair of slideable strips on each side and end rail, the adjacent ends of the strips being overlapped and bevelled, an operating screw and nut associated with the bevelled ends of the strips for moving the bevelled ends over each other to separate the strips and move them into binding engagement with the legs, said bevelled ends being slotted for the passage of the screw, the outer ends of the strips having end opening slots, and guide pins for the outer ends of the strips carried by the table top and rail and extending through the end slots.

In testimony whereof I affix my signature.
STANLEY WOJTAN.
